UNITED STATES PATENT OFFICE.

WILLIAM G. TEMPLETON, OF COLORADO SPRINGS, COLORADO.

VENDING-MACHINE.

1,317,765.

Specification of Letters Patent.

Patented Oct. 7, 1919.

Application filed December 1, 1917. Serial No. 204,849.

To all whom it may concern:

Be it known that I, WILLIAM G. TEMPLETON, a citizen of the United States, residing at Colorado Springs, in the county of El

5 Paso and State of Colorado, have invented a new and useful Vending-Machine, (Case A,) of which the following is a specification.

This invention relates to vending machines, one of its objects being to provide 10 a simple and compact machine formed of but few parts and which utilizes a delivering member of novel construction mounted to work about a substantially horizontal axis thereby to deliver articles successively 15 from opposite sides of the machine.

Another object is to provide a delivering member having combined with it separate trays for receiving the delivered article and holding them where the user can readily 20 reach them, each of said trays, when in one position constituting a closure for one of the delivery openings of the machine and, when in another position, constituting an actuating element for shifting the delivering member from one position to another.

A further object is to provide simple and efficient check controlled means for releasing the delivery member to permit actuation thereof, said means automatically locking 25 the delivery member immediately prior to the delivery of an article from one side of the machine, thereby to prevent delivery of an article from the other side of the machine unless a check of proper value is inserted.

30 A further object is to provide a delivery member which constitutes means for supporting the contents of the magazine of the machine which operates easily and with practically no friction.

40 With the foregoing and other objects in view which will appear as the description proceeds, the invention resides in the combination and arrangement of parts and in the details of construction hereinafter described and claimed, it being understood 45 that changes in the precise embodiment of the invention herein disclosed, can be made within the scope of what is claimed, without departing from the spirit of the invention.

50 In the accompanying drawings the preferred form of the invention has been shown.

In said drawings:—

Figure 1 is a front elevation of a vending machine embodying the present improvements.

55

Fig. 2 is a section on line 2—2 of Fig. 1.

Fig. 3 is a section on line 3—3 of Fig. 2.

Fig. 4 is a section on line 4—4 of Fig. 2.

Fig. 5 is a section on line 5—5 of Fig. 2.

Fig. 6 is an enlarged central vertical section through a portion of the machine and showing the check controlled locking dog and adjacent parts.

60

Fig. 7 is a perspective view of said locking dog.

65

Fig. 8 is a perspective view of the delivery member.

Referring to the figures by characters of reference 1 designates a base upon which is secured a casing 2, the sides of this casing 70 being provided, at the bottom thereof, with rearwardly projecting extensions 3 connected at their upper ends by a top plate 4. A transverse partition 5 also connects these side extensions 3 and is substantially in line 75 with the back face of the casing 2; the side wall extensions 3, top 4 and partition 5 co-operating to form a housing for the check-controlled mechanism. A removable closure 6 may be provided at the back of this 80 housing.

A removable rear panel 7 is mounted on the back of the casing 2 above and substantially in line with partition 5 thus to give access to the interior of the casing 2.

85

Secured to and extending rearwardly from the front wall of the casing 2 are parallel partitions 8 and a check receiving slot 9 formed in the front of the casing 2 opens into the space between these partitions so 90 as to direct a check onto an inclined check supporting strip 10 which is secured between the partitions 8 and projects rearwardly between two wings 11 which extend from the partition 5 and into the space between the side extensions 3.

A pin 12 is journaled in the wings 11 close to the partition 5 and under the check supporting strip 10 and secured to this pin is a bell crank lever 13 the lower arm of 100 which projects rearwardly beyond the wings 11 and is recessed, as at 14, to constitute a

check holder or support. The other arm of the lever 13 has a terminal finger 15 which projects through an opening 16 in the partition 5 as shown particularly in Fig. 6.

5 Journalled in bearings 17 mounted on the base 1 between the front of the casing 2 and the partition 5 is a shaft 18 which extends rearwardly through the partition 5 and between the side extensions 3. This shaft is 10 located directly under the space between the partitions 8 and serves to support the delivery mechanism of the machine. This delivery mechanism includes a supporting plate 19 adapted to work close to the lower 15 ends of the partitions 8 and which has two wings 20 extending downwardly and secured to the shaft. One of the wings 20 has recesses 21 extending therewith from opposite edges and either of which is adapted to receive 20 the stop finger 15, thus to limit the swinging movement of the plate 19 and the rotation of the shaft 18. A weight 22 is secured between the wings 20 and extending under the plate 19 and outwardly beyond the 25 sides thereof are push devices in the form of delivering trays 23 each of which terminates at its free end in an upwardly extending flange 24 to which is secured a closure plate 25. The delivery trays 23 converge upwardly and are adapted to work within the delivery openings 26 formed in the sides of the casing 2. The plates 25 are so proportioned that when one of the trays 23 is elevated or drawn into the casing 2, the plate 25 attached thereto will close the opening into which said tray extends. A guard 27 is extended outwardly and downwardly from the upper edge of each of the openings 26, and serves to prevent access being had to any 30 of the contents of the casing 2.

It is to be understood that the plate 19 and the delivery trays 23 are located directly under the spaces at opposite sides of the central partitions 8 and which spaces 45 constitute parallel magazines indicated at 28 and 29 respectively. One or more of the walls of each magazine can be provided with openings 30 whereby the contents of the magazine can be seen.

50 That portion of the shaft 18 which projects between the side extensions 3 of the casing supports a member 31 mounted for swinging movement and which is provided, at opposite sides, with coin receiving pockets 32 55 adapted to be brought successively into register with the space between the wings 11. These pockets are of such length as to move into position above the coin supporting end 14 of the lever 13.

60 Suitable means may be used for holding the finger 15 in locking position. For example a spring 33 may connect the partition 5 with a finger 34 extending radially from one end of the pin 12. This spring thus 65 serves to hold the finger 15 normally pressed

into the opening 16 so as to be seated in one of the recesses 21 of the delivery mechanism. Likewise the coin receiving portion 14 of the lever is held normally elevated close to and under one of the coin receiving pockets 32. 70

Under normal conditions the delivery mechanism is so located that the plate 19 is mounted under one of the magazines, thus to support articles in position where they cannot escape through the adjacent opening 75 26, while the articles in the other magazine rest upon one of the trays 23, the plate 25 connected to said tray closing the opening 26 into which the article supporting tray projects. The parts are held in this position 80 by the finger 15 on lever 13 projecting into one of the recesses 21. The weight 22 likewise maintains the parts in these positions by gravity.

When it is desired to remove an article 85 from the machine a check or coin is inserted through the slot 9 and will roll along the strip 10 and between the wings 11 so as to fall into the pocket 32 in line therewith and thus be guided onto the portion 14 of lever 90 13 and which is located directly under the pocket. The weight of the coin or check will be sufficient to shift lever 13 so as to withdraw the finger 15 from the recess 21 in which it is located. By now pushing laterally upon the plate 25 on the end of the projecting push device or tray 23, the delivery member can be swung laterally and the advancing edge of the plate 19 will thrust against the article resting on the outwardly moving tray 23. Thus one of the articles in one of the magazines will be carried outwardly with the tray through the opening 26 while the opposed tray which is being thrust inwardly will move to position 100 under the other magazine so as to receive the lowermost article therein. The plate 19 moves from under one magazine to position under the other magazine as will be obvious. Just prior to the arrival of the delivery 105 mechanism at the point where the article will be free to be withdrawn from the machine, the finger 15 moves into one of the recesses 21 thus to prevent return movement of the delivery mechanism to its initial position. Consequently it becomes impossible, by manipulating the apparatus, to get more than one article by depositing one coin or check. When the delivery mechanism begins to move after being unlocked, the member 110 31 also shifts so as to bring another coin pocket 32 into position in line with the base container wings 11. The outer wall 35 of each of the pockets 32 extends downwardly to support a check on edge upon the portion 115 14 of lever 13 and as soon as member 31 moves out of its extreme position the check will lose this support and fall off of the lever into the space back of the closure 6.

It will be seen that a machine such as 120 130

herein described is very simple, durable and compact and is advantageous because of the few parts necessary in its construction. While it is useful for dispensing articles of 5 different kinds, it has been found especially advantageous as a machine for dispensing boxes of matches.

Attention is called to the fact that the weight 22 serves to facilitate the operation 10 of the mechanism, this weight shifting the delivery mechanism to either limit of its movement as soon as said mechanism has passed its dead center.

What is claimed is:—

15 1. A vending machine including a magazine having opposed outlet openings, a delivery member mounted to rock below the magazine and between said openings, said member constituting a support for articles 20 within the magazine, and having oppositely extending trays movable within the respective openings, a closure carried by each tray, and means for automatically locking the delivery member against return movement 25 during its rocking movement in either direction.

2. A vending machine including a magazine having opposed outlet openings, a member movably mounted under the magazine 30 and between the openings, means for holding said member normally at either of its two limits of movement, trays extending from opposed portions of said member and into opposed openings, each of said trays constituting a push device for shifting the member from one limit of movement to the other, means carried by each tray for closing the opening in which the tray is mounted when 35 said tray is at one limit of its movement 40 and for supporting a delivered article when the tray is at the other limit of its move-

ment, and means for automatically locking the member and trays against return movement while being moved toward either limit of their movement.

45

3. A vending machine including a magazine having opposed outlet openings, a member movably mounted under the magazine and between the openings, means for holding said member normally at either of its two 50 limits of movement, trays extending from opposed portions of said member and into opposed openings, each of said trays constituting a push device for shifting the member from one limit of movement to the other 55 and means carried by each tray for closing and opening in which the tray is mounted when said tray is at one limit of its movement and for supporting a delivered article when the tray is at the other limit of its 60 movement.

4. A vending machine including a magazine having opposed outlet openings, push devices mounted to rock between and move within the respective openings and movable 65 alternately to close their respective openings, each of said push devices constituting a delivery tray, means for locking the push devices when approaching either limit of their movement, and means for automatically 70 completing the movement of said devices after an initial impulse in either direction, and subsequent to the unlocking of the devices.

In testimony that I claim the foregoing 75 as my own, I have hereto affixed my signature in the presence of two witnesses.

WILLIAM G. TEMPLETON.
